CONSTRUCTION OF ROOFINGS, PARTITIONS, AND THE LIKE

Herbert Leonard Plummer and Davis Lambert
Irwin, London, EnglandApplication April 4, 1932, Serial No. 603,190, and
in Great Britain April 22, 1931

8 Claims. (Cl. 189—34)

This invention relates to the construction of roofings, decks, partitions and like structural surfaces comprising a substantially flat panel of the kind provided adjacent to one of its sides with a plain flange and adjacent to an opposite side with a curved flange adapted to interengage with the plain flange of a similarly formed adjacent panel, and with reinforcing ribs extending lengthwise thereof, the extremities of which are adapted to interengage with the extremities of the reinforcing ribs of a similarly formed adjacent panel.

The invention consists in a panel of the kind specified formed adjacent to one of its ends with cut away portions adapted to facilitate the interengagement of the extremities of the ribs with the extremities of the ribs of a similarly formed adjacent panel, and adjacent to its opposite end with further cut away portions adapted to facilitate access to and adjustment by means of a suitable tool of fastening means passed through holes in the bases of the ribs.

Preferably in accordance with the invention the cut away portions at both ends of the panel are located above and adjacent to the extremities of the ribs, thereby exposing at one end of the panel portions the interior surfaces of the ribs into engagement with which the extremities of the ribs of a similarly formed adjacent panel are adapted to be admitted, and at the other end of the panel portions the interior surfaces of the bases of the ribs upon which the fastening means are adapted to be tightened down in order to lock the interengaging extremities of the ribs of adjacent panels together and to a structural support.

Conveniently the edges of the cut away portions or certain thereof may be formed to provide seatings for covers which may be arranged in position within the cut away portions after the panel has been secured in position, thereby ensuring that the resultant structure will expose a substantially flat surface.

Where, for instance, the reinforcing ribs are provided with flanges secured to the underneath side of the panel, the cut away portions may be formed so as to expose parts of the said flanges which may be employed as seatings for the covers, and optionally with such a construction the recesses adjacent to the extremities of the ribs in which the extremities of the ribs of an adjacent panel are adapted to be engaged may be so formed that the flanges of the inserted ribs will contact with the flanges of the exposed portions of the ribs into engagement with which they are

adapted to be admitted, thereby ensuring that in the case of overlapping panels the thickness of the structural surface where the panels overlap will be only that of the double thickness of the sheet from which a single panel is formed. 60

In order that satisfactory engagement may be secured between the reinforcing ribs of the panel and the reinforcing ribs of an adjacent panel, portions of the ribs at one end of the panel may be formed of smaller cross section 65 than the portions of the ribs adjacent to the opposite end of the panel, and for promoting satisfactory overlapping of the panels when a plurality of the same are assembled together on a structural surface, and for ensuring that the 70 flanges on both sides of the said panels shall in such a surface lie in a substantially straight and uninterrupted line, both the curved flange and the plain flange at their ends adjacent to the portions of the ribs of smaller cross section may 75 be provided with cut away portions against the ends of which the ends of the flanges of an adjacent panel may be caused to abut, while both flanges at the opposite extremity of the panel may be provided with pressed in portions over 80 which the extremities of the flanges adjacent to the cut away portions therein of an adjacent panel are adapted to overlap.

The invention also extends to roofings, decks, partitions and like structural surfaces comprising a plurality of panels as above described arranged in interlocking engagement to form a substantially flat surface, which may thereafter be treated as for instance by the application thereto of flexible roofing material in sheet form 90 for example of the character of bituminized felt between which and the surfaces of the panels there may optionally be arranged a layer of heat insulating material. 85

The invention will be described further in detail by way of example with reference to the accompanying drawings, in which— 95

Figure 1 is a view of one construction in accordance with the invention;

Figure 2 is an underneath view of the construction illustrated in Figure 1; 100

Figure 3 is a fragmentary view of an alternative construction.

Figure 4 is a view illustrating the method of assembling together a plurality of panels constructed in the manner illustrated in Figures 1 to 3. 105

Figure 5 is a view of a section along the line V—V of Figure 4.

Figure 6 is a similar view to the view shown in 110

Figure 5 but illustrating a modified form of construction.

In the drawings, 1 indicates a substantially flat rectangular metal sheet provided adjacent to one of its sides with a downwardly directed plain flange 2 and adjacent to its opposite side with a further downwardly directed flange 3 having an upwardly curved portion 4 forming one side of a groove 5 in which the plain flange of an adjacent similarly formed panel is adapted to engage.

The downwardly extending portions of both flanges at one end of the panel are formed with cut away portions, the extremities, 6, 7, of which are adapted to abut against the ends of the flanges of an adjacent panel, while adjacent to the opposite end of the panel the flanges are formed with pressed in portions 8, 9, over which those portions 10, 11 of the flanges of a similarly formed panel adjacent to the cut away portions therein are adapted to overlap.

Extending lengthwise of the metal sheet are a plurality of metal reinforcing ribs 12 in the form of rectangular section channel members provided with flanges 13 welded to the underneath side of the sheet. The flanges may alternatively be soldered, riveted or secured in any other manner to the sheet.

Adjacent to that end of the panel at which the flanges are provided with cut away portions, the reinforcing ribs are joggled to form portions 14 of smaller cross section than the cross section of the ribs at their opposite ends, and above each of the said portions of smaller cross section the sheet is formed with a cut away portion of substantially rectangular form 15 exposing both a portion of the interior of the reinforcing ribs and also portions 16 of the flanges thereon which are adapted for use as seatings for rectangular sheet metal covers 17 which may be located thereon to close the said cut away portions after the panel has been secured in position on the structure.

The object of exposing the interiors of portions of the ribs at this end of the panel is to facilitate access to suitable securing means for instance hook bolts which may be passed through holes in the bases of the ribs and the nuts on the bolts may be tightened down on the said bases by means of a suitable tool in order to secure the interengaging extremities of the ribs of adjacent panels to a purlin, rafter, or like structural member.

In a like manner the panel is provided adjacent to its opposite end above portions of the ribs adjacent to their extremities with further cut away portions 18 exposing both the interiors of the end portions of the ribs and portions of the flanges thereon, and within the exposed portions of the ends of the ribs the joggled ends 14 of the ribs of an adjacent panel are adapted to be engaged, and when in this position hook bolts or the like may be passed through the overlapping base portions of the ribs and secured in position on a structural member in the manner above indicated.

An alternative form of construction is shown in Figure 3 in which the grooved flange 3 is cut away at an opposite end of the panel from that illustrated in Figures 1 and 2, while the flange 2 remains of the same form as that illustrated in the said figures.

In cases where it is desired that at the points where the panels overlap the effective thickness of the surface should be only that of two panels,

the ends of the ribs instead of being of the form illustrated in Figure 5 may be of the form illustrated in Figure 6, in which figure the flanges adjacent to the ends of the ribs on the upper panel are shown as being narrower than the cut away portions on the lower panel, so that when the ends of the two panels are in engagement with one another the flanges on the ends of the ribs of the uppermost panel will seat directly on the flanges on the ends of the ribs on the lowermost panel.

While in the above description certain details of construction have been furnished to illustrate by way of example certain suitable manners of carrying the invention into effect, it is to be understood that the invention is not limited to the details of construction set forth, and numerous other manners of carrying the invention into effect may be employed without exceeding the scope of the invention.

We claim:

1. A substantially flat panel adapted for use in the construction of structural surfaces comprising adjacent to one of its sides a plain flange and adjacent to an opposite side a curved flange adapted to interengage with the plain flange of a similarly formed adjacent panel, reinforcing ribs extending lengthwise of the panel, the ends of which ribs are adapted to interengage with the extremities of the reinforcing ribs of a similarly formed adjacent panel, cut away portions formed adjacent to one end of the panel adapted to facilitate the interengagement of the extremities of the ribs with the extremities of the ribs of a similarly formed adjacent panel, and further cut away portions formed adjacent to the opposite end of the panel adapted to facilitate access to and adjustment by means of a suitable tool of fastening means passed through holes in the bases of the ribs.

2. A panel as claimed in claim 1 in which the cut away portions at both ends of the panel are located above and adjacent to the extremities of the ribs, thereby exposing at one end of the panel portions of the interior surfaces of the ribs into engagement with which the extremities of the ribs of a similarly formed adjacent panel are adapted to be admitted and at the other end of the panel portions of the interior surfaces of the bases of the ribs upon which the fastening means are adapted to be tightened down in order to lock the interengaging extremities of the ribs of adjacent panels together and to a structural support.

3. A substantially flat panel adapted for use in the construction of structural surfaces comprising adjacent to one of its sides a plain flange and adjacent to an opposite side a curved flange adapted to interengage with the plain flange of a similarly formed adjacent panel, reinforcing ribs extending lengthwise of the panel, the ends of which ribs at one end of the panel are formed of smaller cross section than the portions of the ribs at the opposite end of the panel so that a satisfactory engagement may be effected between the ribs at one end of the panel and the ribs at the end of an adjacent panel, cut away portions formed adjacent to one end of the panel adapted to facilitate the interengagement of the extremities of the ribs with the extremities of the ribs of a similarly formed adjacent panel, and further cut away portions formed adjacent to the opposite end of the panel adapted to facilitate access to and adjustment by means of a suitable tool of fastening means passed through holes in the

- bases of the ribs, both the curved flange and the plain flange at their ends adjacent to the portions of the ribs of smaller cross section being formed with cut away portions against the 5 ends of which the flanges of an adjacent panel are adapted to abut, while both flanges at the opposite extremity of the panel are provided with pressed in portions over which the extremities of the flanges adjacent to the cut away portions 10 therein of an adjacent panel are adapted to overlap.
4. A structural surface formed of interlocking substantially flat panels, each of which comprises adjacent to one of its sides a plain flange and 15 adjacent to an opposite side a curved flange adapted to interengage with the plain flange of a similarly formed adjacent panel, reinforcing ribs extending lengthwise of the panel, the ends of which ribs are adapted to interengage with 20 the extremities of the reinforcing ribs of a similarly formed adjacent panel, cut away portions formed adjacent to one end of the panel adapted to facilitate the interengagement of the extremities of the ribs with the extremities of the ribs of a similarly 25 formed adjacent panel, and further cut away portions formed adjacent to the opposite end of the panel adapted to facilitate access to and adjustment by means of a suitable tool of fastening means passed through holes in 30 the bases of the ribs.
5. A structural surface as claimed in claim 4 in which the cut away portions at both ends of the panel are located above and adjacent to the extremities of the ribs, thereby exposing at one 35 end of the panel portions of the interior surfaces of the ribs into engagement with which the extremities of the ribs of a similarly formed adjacent panel are adapted to be admitted and at the other end of the panel portions of the 40 interior surfaces of the bases of the ribs upon which the fastening means are adapted to be tightened down in order to lock the interengaging extremities of the ribs of adjacent panels together and to a structural support.
- 45 6. A structural surface formed of interlocking substantially flat panels, each of which comprises adjacent to one of its sides a plain flange and adjacent to an opposite side a curved flange adapted to interengage with the plain flange of a similarly formed adjacent panel, reinforcing ribs extending lengthwise of the panel, the ends of which ribs at one end of the panel are formed of smaller cross section than the portions of the ribs at the opposite end of the panel so that 50 a satisfactory engagement may be effected between the ribs at one end of the panel and the ribs at the end of an adjacent similarly formed panel, cut away portions formed adjacent to one end of the panel adapted to facilitate the interengagement of the extremities of the ribs with the extremities of the ribs of a similarly formed adjacent panel, and further cut away portions formed adjacent to the opposite end of the panel adapted to facilitate access to and adjustment by means of a suitable tool of fastening means passed through holes in the bases of the ribs.
- 55 7. A structural surface formed of interlocking substantially flat panels, each of which comprises adjacent to one of its sides a plain flange and adjacent to an opposite side a curved flange adapted to interengage with the plain flange of a similarly formed adjacent panel, reinforcing ribs extending lengthwise of the panel, the ends of which ribs at one end of the panel are formed of smaller cross section than the portions of the ribs at the opposite end of the panel so that 60 a satisfactory engagement may be effected between the ribs at one end of the panel and the ribs at the end of an adjacent similarly formed panel, cut away portions formed adjacent to one end of the panel adapted to facilitate the interengagement of the extremities of the ribs with the extremities of the ribs of a similarly formed adjacent panel, and further cut away portions formed adjacent to the opposite end of the panel adapted to facilitate access to and adjustment by means of a suitable tool of fastening means passed through holes in the bases of the ribs.
